BOBBIN HANDLING MECHANISM

Russell P. Drake, Caledonia, Ill., assignor to
 Barber-Colman Company, Rockford, Ill., a corporation of Illinois

Application September 11, 1944, Serial No. 553,507

37 Claims. (Cl. 242—1)

1

This invention pertains to bobbin winding machines generally and more especially is concerned with bobbin handling devices therefor.

The primary object of the invention is to provide an automatic bobbin handling mechanism for machines of the character described which will so perform the functions of doffing and of storing a wound bobbin that the machine may be employed to wind delicate yarns, such as a fine cotton, nylon or rayon.

More specifically stated, the invention aims to provide a doffing mechanism which will receive a wound bobbin from the winding spindle of a winding machine and deliver the same to a storage device, such as a slowly moving conveyer, without subjecting the material wound on the bobbin to any surface which will injure it.

Another object of the invention is to associate a doffing mechanism with a donning device in a manner such that the two operations may be performed with but a single transfer mechanism.

A further object of the invention is to provide an improved clamping and shearing device for a bobbin winding machine which is operable in timed relation with its doffing mechanism.

The objects of the invention thus generally stated, together with other and ancillary advantages, are attained by the construction and arrangement shown by way of illustration in the accompanying drawings forming a part hereof, in which:

Figure 1 is a front elevational view of one end of a winding machine with parts thereof broken away, showing the main cam shaft and associated instrumentalities for driving and controlling the bobbin handling mechanism embodying the present invention.

Fig. 2 is a transverse section taken approximately in the plane of line 2—2 of Fig. 1.

Fig. 3 is a detail view of the ratchet device for the pin chain conveyer.

Fig. 4 is a fragmentary front view of the bobbin transfer mechanism showing its relationship to the spindle and wound bobbin conveyer when positioned to receive an empty bobbin.

Fig. 5 is a view similar to Fig. 4 showing the bobbin carrier arm positioned to hold an empty bobbin in place for reception in the spindle and a wound bobbin for ejection onto the conveyer.

Fig. 6 is a view in partial section showing the 50 in position to be clamped to the spindle and the

2

mechanism for ejecting wound bobbins from the doffing trough onto conveyor.

Fig. 7 is a plan view showing in detail the bobbin carrier arm, shear mechanism, bobbin carrier trough, plunger and chain guides.

Fig. 8 is a front detail view showing the clamping and shearing blades of the clamping device.

Fig. 9 is a side view of the shearing mechanism.

10 In carrying out my invention, I provide a traveling storage medium, preferably in the form of an endless chain conveyer equipped with individual supports to which the wound bobbins may be successively transferred upon release from the winding mechanism. The conveyer is advanced with a step-by-step motion to present the individual supports successively into position for the reception of wound bobbins from a transfer mechanism timed with respect to the winding mechanism and the conveyor. While being wound the bobbins are advantageously supported for rotation on a horizontal axis and the storage conveyer is vertically disposed on one side of such axis, while on the other side, is an empty bobbin supply means including a magazine from which empty bobbins may be delivered one by one to the winding mechanism. With this arrangement in view, the bobbin transfer mechanism is especially constructed for the performance of the additional function of taking an empty bobbin from the magazine and delivering the same to the winding mechanism simultaneously with the transfer of a wound bobbin to the conveyer.

In its present illustrative embodiment, the invention is shown as being applied to a machine of the type which is composed of a plurality of units arranged side-by-side in a suitable supporting framework and having a common driving and control mechanism. In general, each unit comprises (Figs. 1 and 2) a winding mechanism A including a horizontally disposed spindle, an empty bobbin supply mechanism B on one side of the spindle, a storage mechanism C on the other side equipped with individual bobbin supports, 40 and a transfer mechanism D designed to operate between the empty bobbin supply mechanism, the winding spindle and the storage mechanism and including two receptacles, one for taking an empty bobbin from the magazine and placing it 45 and a receptacle for receiving a wound bobbin from the spindle and placing it in position to be clamped to the spindle and the

3

other for receiving a wound bobbin from the spindle and transferring the same to the storage mechanism.

The empty bobbin supply means B comprises, as herein shown, an upright magazine 10 arranged to support a vertical stack of empty bobbins. At its lower end it is equipped with means generally designated 11 for releasing empty bobbins one at a time to the transfer mechanism D, as hereinafter more fully set forth.

The bobbin winding mechanism forms per se no part of the present invention. As shown, it is of the type disclosed in copending application, Serial Number 450,129, filed July 8, 1942, by Brooks Marcellus, now Patent No. 2,409,639, issued October 22, 1946. In brief, it comprises a spindle 12 equipped with a chuck 12a, for coaction with a centering slide 13 to rotatively support an empty bobbin 15 upon which the bobbin filling is wound. In the present instance, the machine is intended for use in producing filling wound bobbins known as cops or pirns. Accordingly, the winding mechanism also includes a unidirectionally rotating traversing cam sleeve 14 encircling the spindle and mounted on a slide 14a for movement axially of the bobbin during the winding operation.

The storage mechanism C comprises in the preferred embodiment an endless chain conveyer 16 vertically disposed and equipped with a series of pins 17 constituting the individual supports for wound bobbins. The pins are mounted on the chain in spaced parallel relation so as to be presented successively to a bobbin loading position parallel with but offset rearwardly of the bobbins as they are being wound (see Fig. 2).

The driving and control mechanism common to the several winding units is generally designated by the numeral 20 (Fig. 1). It provides a means for operating the bobbin transfer mechanisms, the shearing devices, the storage conveyers and other instrumentalities of all units. A mechanism of this type is fully described in said Patent No. 2,409,639. Since it forms per se no part of the present invention, it will not be treated in detail here. In brief, it comprises a main cam shaft 21 which carries separate cams for driving each of the various instrumentalities mentioned above. This shaft in turn is driven by means of a motor 22 operating through a drive 23, a shaft 24 for driving said cam shaft and suitable gearing, not shown. The cam shaft 21, in addition to furnishing power, also controls the timing of the various operations such as donning, doffing, etc. with respect to that of winding as described in said copending application.

Referring now to Figs. 4 and 5, the bobbin transfer mechanism comprises in the present preferred embodiment of the invention, a pivotally mounted upright carrier arm 25 to which are attached a cradle 26 and a trough 27. The form taken by these two bobbin receiving receptacles and their mode of attachment to the arm 25 is dictated largely by the manner in which they function and by the fact that they are both mounted on the same arm.

The first receptacle must support and hold an empty bobbin for a period of time and then release it after the same has been clamped in winding position. To do this with a minimum number of working parts, the cradle 26 is employed. In the present embodiment, it takes the form of a U-shaped bracket whose arms are bifurcated to form receiving fingers 28-29 and 30-31 (Fig. 7) respectively for the tip and head

4

of a bobbin. In order that the fingers 29 and 31 may not be fouled (see Fig. 5) when the carrier arm 25 is returned to its retracted position, the cradle 26 is yieldably attached to the arm by means of a pin 32 about which it is free to move. It is held in its normal position by a tension spring 33 which urges a lug 34 forming a part of the bracket against a stop 35.

For receiving wound bobbins onto the transfer mechanism the receptacle must be shaped to hold a bobbin which is dropped from the chuck 12a and for this purpose the trough 27 is employed. Like the cradle 26, the trough 27 is yieldably attached to the arm 25 since it is desired to have it move substantially horizontally to its discharge position forwardly of the conveyer 16. In this case, an arm 37 which supports the trough is attached to the arm 25 by means of a bracket 38. The arm 37 is thus permitted to pivot about a point 39, and under the action of a tension spring 40, a roller 41 carried on a movable base plate 42 (Fig. 6) of trough 27 is held against a fixed guide bracket 43. Thus, as the arm 25 moves from its position illustrated in Fig. 4 to the one shown in Fig. 5, the roller 41 moves along the track 43 into a position in front of the conveyer 16 as shown. Here, the level of the guide bracket 43 establishes a datum to which each of the pins 17 may be indexed by means associated with the conveyer later to be described. As the arm 25 returns to its normal position, it operates the escapement 11. The latter is in the form of a bar pivotally supported at its upper end (Fig. 1) and having a laterally projecting finger 11a, the member being urged by a torsion spring 11b in a direction to carry the finger 11a toward the magazine. When the arm 38 is moved into the position shown in Fig. 4, the escapement member is retracted against the action of the spring 11b, causing it to release the bobbin from the magazine into the cradle 26, the remaining bobbins being supported by the bobbin thus released. As the released bobbin is moved out from under the next lowermost bobbin in the initial portion of the ensuing donning stroke of the arm 38, the finger 11a is carried by the spring 11b into position beneath said next lowermost bobbin so as to support the stack of bobbins in the magazine until the arm returns and withdraws the finger 11a for the release into the cradle of the next bobbin.

In addition to being movable transversely with respect to the spindle axis, the trough 27 is also mounted for movement parallel thereto by a special mechanism which causes the discharge of a bobbin from the trough onto the conveyer. To provide for this mobility, the trough 27 is attached to the movable base plate 42 which in slides in grooves or ways 44 channeled in the arm 37.

Since the express function of the transfer mechanism is to transfer bobbins from fixed points to fixed points, it is obvious that its movement between these points must be controlled in order that its proper alignment with the apparatus located at these points will be assured. To provide for the proper registration of the cradle 26 and the trough 27 with respect to the magazine, the spindle and the conveyer, the movement of the arm 25 on a shaft 45 about which it rotates is restricted by means of a pair of adjustable stops 46 and 47 clamped onto a boss 48 in which the shaft 45 is journaled. By the adjustment of the stop 46, the counterclockwise rotation of the arm 25 is restricted to an extreme position which places the cradle 26 directly under the magazine

10 and similar regulation of the stop 47 positions it accurately before the chuck 12^a for clockwise rotation. In the first of these positions, the trough 27 rests under the winding spindle, and in the second it occupies what is termed as its delivery position. The horizontal alignment of the trough 27 with the conveyer 16 is made by proper location of the latter, the horizontal distance between the bobbin axes of the cradle and the trough being fixed by their selected dimensions.

The movement of the arm 25 between the above established limits is effected by means of an arm 49 (one for each unit) also pivoted on the shaft 45 (Fig. 2) and operatively connected to the arm 25 through the shaft 45 and an overload detent 50. The arm 49 is connected to a reciprocating bar 51 which extends longitudinally of the machine so as to serve all units, and is actuated in a horizontal plane by a barrel cam 52 in the common drive and control mechanism 20. This cam is mounted on the main cam shaft 21 and cooperates with a cam follower 53 which is pivoted at 54 and connected to the bar 51 by a link 55. As the cam 52 is rotated, the follower 53 is cammed in the groove 56 and the bar 51 is rocked to move the bobbin transfer mechanism of all units together.

Closely associated with the bobbin transfer device D just described, is a mechanism 57 controlling both the movement of the centering slide 13 and also the ejection of a wound bobbin from the trough for delivery to the storage chain. It comprises a cam operated pinion 58 (Fig. 2) which meshes with a rack 59 on the centering slide 13 to move the latter toward and away from the spindle 12 during the process of mounting and releasing a bobbin. Moreover, it includes a plunger 60 for shifting the trough 27 rearwardly toward the conveyer 16 to discharge a wound bobbin 61 onto a pin 17 of the storage chain.

Like the previously described instrumentalities, the slide and plunger mechanism 57 is actuated from the common driving and control mechanism 20. Here (Figs. 1 and 2) a cam 62 on the main cam shaft 21 controls the operation of the centering slide 13 through a bell crank 63 which is pivoted at 64 and carries a cam follower 65 on one end and a gear segment 66 on the other. The segment 66 meshes with and drives a gear 67 (Fig. 1) keyed to the extreme end of a longitudinally extending shaft 68 on which gears 58 (one for each unit) are also fixedly attached.

The bobbin ejecting plungers 60 of the several units are also actuated by the cam 62. To this end, the gear 67 meshes with a gear 69 fast on a rock shaft 70 parallel with the shaft 68 and having keyed thereto a toggle arm 71 (Fig. 6). This toggle arm is connected by a second toggle arm 72 to a crank 73 fixed on a rock shaft 74 extending lengthwise of the machine and having attached thereto by means of overload detents 74^a a series of plunger arms 75 (one for each unit). Each arm 75 is connected to its plunger by a pin-and-slot connection 76 which operates the plunger to move the trough 27 toward the conveyor 16.

Since the bobbin transfer mechanism of which the trough 27 is a part, moves transversely relative to the motion of the plungers 60 and independently thereof, a disengageable connection between these members is provided. In the illustrative embodiment, this connecting means takes the form of a head 77 (Fig. 6) attached to each plunger and formed with a channel 77^a to receive the roller 41. When the plunger is in its

normal retracted position (Fig. 7), this channel is aligned with a groove 78 formed in the guide bracket 43 which constitutes a track for the roller 41. As the trough 27 is moved to the right (Fig. 7) the roller 41 enters the channel in the head to connect the plunger to the trough, the groove and channel being flared to facilitate the entry and withdrawal of the roller in the head 77.

10 In its rearward movement the plunger 60 operates to compress a spring 79 (Fig. 6), which returns the trough 27 to its normal position after a wound bobbin has been discharged. This spring is retained in a bore 79^a in an enlarged portion of the arm 37 provided for this purpose and operates against a movable bracket 80 attached to the base plate 42 and supporting the roller 41. The plate 42 has a stop lug 81 for engagement with a coating stop surface 82 on the arm 37 to prevent the trough from being forced off of the arm by the spring 79.

As previously stated, all operations are performed in timed relationship with each other. In the present instance, the gear 58 is rotated to withdraw the centering slide 13 and a wound bobbin is released from the spindle 12 which falls into the trough 27. Rotation of the gear 58 is also accompanied by the rocking of the shaft 70 and the toggle link 71 through approximately 180° of displacement. As the latter passes through its point of maximum throw in one direction, arm 75 is rocked about shaft 74 and plunger 60 is moved forward in an idle stroke. Before the toggle link 71 approaches a point of second maximum thrust in the opposite direction of its rotation, the trough 27 is moved into position before the conveyer 16 and the roller 41 has entered the head 77 on the plunger 60. When the second point of maximum throw is reached, the trough and plunger being thus connected are moved together toward the conveyer and the wound bobbin 61 is pressed onto one of the pins 17 to complete the transfer operation.

It will be observed that the complete transferring operation of the wound bobbin 61 from the spindle to the conveyer is made without subjecting the filling thereof to contact with any surface that would cause injury to it. Thus it will be noted from Fig. 6 that trough 27 is shaped to support the wound bobbin 61 solely by its tip 83 and its head 84. This prevents the filling from touching the interior of the trough at any time. Moreover, movement of the bobbin with the trough does not disturb this condition. Thus, as trough 27 moves toward the conveyer, the end thereof bears against the tip 83 and presses it onto the pin 17 without relative movement of trough and bobbin. When the bobbin is firmly positioned on the pin, it is supported in a horizontal position as will presently be described. Consequently, as the trough is retracted and the support of tip 83 is withdrawn, the bobbin is prevented from sagging and the trough is returned without the filling of the bobbin dragging on the bottom surface.

The storage-conveyer mechanism to which filled bobbins are delivered by the foregoing transfer mechanism, will now be described in connection with Figs. 2, 4, 6 and 7. In general, this storage-conveyer mechanism provides a means for taking bobbins from the transfer mechanism one at a time and storing a number of them separately for an interval of time. In the present embodiment of the invention, this period of time is provided for by moving the stor-

ager means slowly over a long vertical run, such movement being usefully employed to convey the bobbins to a convenient place in the machine where they may be removed by hand. The interval of time required for a bobbin to make this vertical run preferably provides a time period of sufficient duration to enable a single operator to attend a number of units or machines, since she can remove the continuously advancing bobbins at any point in their run.

As illustrated in the drawings, the storage-conveyer heretofore generally designated 16, comprises an endless chain 85 which is carried over a plurality of sprockets 86, 86^a, 86^b and 86^c suitably supported on the machine frame and driven by a ratchet drive 80 (Fig. 2). This chain is advanced in step-by-step fashion and moves the bobbins deposited on the pins 17 vertically from the level of the trough 27 to the top of the machine. During this run the bobbins are successively presented for removal.

The chain 85 is made up of a number of links 85^a to which are attached at spaced intervals cross-bars 87. These bars are fixed to their respective links by a pair of L-shaped brackets 87^a, and rigidly support the pins 17. At opposite ends, the bars are beveled at 88 for reasons which will be developed later. Each bar also supports a spring clamp 89 (Fig. 6) which engages rings 84^a on bobbin head 84 to hold the bobbin in place on the pin once it is deposited there.

Each of the pins carried on the chain must be guided vertically with respect to the trough 27 and each should be firmly held while a bobbin is being pressed onto it especially during the retraction of the trough 27 to avoid injury to the filling as above set forth. Further, after a number of bobbins have been deposited onto a section of the chain, it is important that means be provided to prevent that section from bending or sagging and thereby maintain the bobbins in a horizontal position. Such are the functions of a clamping device 91 and coacting guides 92 and 93 (Fig. 6).

The device 91 comprises two spring pressed arms 94 (Fig. 4) pivoted at 95 on a casting 96 fast to the frame of the machine. These arms carry a pair of hardened members 97 which are notched at 98 to engage and hold a shouldered portion 99 of the pins 17 under the action of springs 100. The members 97 are beveled on their lower rear side at 101 and cooperate with the beveled edges 88 of the bars 87 to hold the chain firmly against the guide 93 which is in the form of an elongated bar. For coaction with the chain, this bar has a face 102 providing a track for the chain and the projecting portions of the links act as flanges which guide the chain along this track. For easy movement of the chain onto the bar, a bevel 103 is cut in its face at the lower end of the bar.

As the chain is advanced vertically, it is further guided and held by guide 92. This guide (Fig. 7) is fashioned from two channeled side plates 104, whose channels 105 form tracks in which the cross bars 87 slide. These channels run parallel with the chain and are so dimensioned as to permit free running of the chain and at the same time prevent the turning of the bars 87 about their longitudinal axes under the gravitational torque of wound bobbins riding on the pins. The plates 104 are separated by a space bar 106 which is rigidly attached to bar 93 as a support for the guide.

One of the important features of the conveyer 16 is its drive mechanism 98, which imparts a step-by-step advancing or indexing movement to the storage chain 85 and indexes the pins carried thereon into position with respect to the trough 27. This device is attached to the housing of drive control mechanism 20 (Fig. 1) and is operated thereby. Thus a chain index cam 107 mounted on the main cam shaft 21 rocks an arm 108 to turn a shaft 110, the arm having a follower 109. Keyed to shaft 110 is an arm 111 which has an adjustable tension spring 112 (Fig. 2) attached thereto that holds cam follower 109 in contact with cam 107. The arm 111 is connected to an arm of a bell crank 113 (Fig. 3), loosely mounted on an indexing shaft 114, by means of an adjustable link 115. The other arm of the crank 113 carries a pawl 116 which drives a ratchet wheel 117, said pawl being held in engagement with the wheel by a spring 118. The ratchet wheel 117 is keyed to the shaft 114 and drives the same. As the shaft 114 is rotated, the sprocket 86^c (one for each unit) is turned to advance the chain 85 through one increment of movement and this positions one of the pins to have a filled bobbin pressed onto it. A spring impelled holding pawl 119 acting against the ratchet 117 is provided to prevent the weight of filled bobbins from driving the chain in the wrong direction. Since the ratchet 117 initiates the movement of the chain 85 at the same time that the plunger 60 is withdrawing the trough 27 of the transfer mechanism 18, and further since the timing of these movements are such as to require it, a notch 120 (Fig. 7) is cut in the trough to permit the pins 17 to pass as the chain is advanced.

Operating in timed relation with the bobbin transfer mechanism D is a clamping and shearing device 121 (Figs. 7, 8 and 9), whose functions are to clamp the strand during the donning operation and subsequently to shear it from a wound bobbin which has been released from the winding mechanism onto the transfer device, all as fully set forth in said copending application.

In the present instance the clamping and shearing elements proper are attached to a horizontal plate 123 (Figs. 7, 8 and 9) which is situated below and to the rear of chuck 12^a and is fixed to the machine's frame 124 by a bracket 125. Carried on the bottom of this plate is a bell crank 126 (Fig. 7) carrying a pair of blades 127 and 128. The blade 127 is mounted adjacently to the plate and its leading edge is rounded so as to clamp the strand between it and the plate when the blades are moved across a notch 129 in the plate 123 into which the strand is drawn. After the strand is clamped thereby, continued movement forces the blade 128, whose leading edge is sharpened, against a stationary arm 130 to sever the strand.

The movement of the blades 127 and 128 is effected by rocking the bell crank 126 about its pivot 131 against the tension of a spring 132 which holds the same in normal position against a stop 133. The bell crank in turn is moved by a rack bar 134 supported to reciprocate in a plane parallel to the axis of the bobbin being wound and carrying on its forward end a bracket 135 normally occupying a position adjacent the rear end of the trough. At the end of its extreme rearward movement, a lug 136 on the bracket 135 engages one arm of the bell crank 126 to operate the clamping and shearing elements as above described.

The rack bar 134 is also utilized in drawing the running strand into the shearing device 121. Thus a pair of wire fingers 137 and 138 attached to the bracket 135 on the rack bar 134 is adapted to snare and retract the strand, which extends from the yarn mass to the wound bobbin dropped in trough 27 and draw it into the shearing device on the retracting stroke of the arm. The finger 137 is straight and is located in front of and above the shearing elements while finger 138 is bent and located below and rearwardly of the finger 137 so as to pass underneath the blades (Fig. 9) when the arm is retracted.

Since the bar 134 is in its retracted position during the donning operation, bracket 135 offers an excellently positioned mounting for a bobbin guide plate 139 (Fig. 9). This plate prevents a bobbin from shifting rearwardly of the chuck 12^a as the bobbins are being shifted to the winding position. The bracket 125 provides a similar mounting for a plate 140 which is fashioned in the form of an apron beneath the shearing device. Its sloping surface tends to cam the wound bobbins forward as they fall from the spindle and position them in the trough 27 so that their heads will be disposed forwardly of the chain pins on the conveyer 16 when the transfer device moves to position them.

It will be apparent that the shearing operation must occur before a wound bobbin, which has been dropped into the trough 27, is moved into position before the conveyer or wastage of yarn will result. Accordingly, the strand is sheared before the arm 25 is moved toward the conveyer and this timing is provided from the central drive control 20 from which the shearing device is operated.

Here, as with the other instrumentalities described, the mechanism is operated by a cam driven by the main cam shaft 21. This cam is in the form of a groove 141 (Fig. 2) cut in one face of a gear 141^a (Fig. 1) for receiving a roller follower 142 carried by an arm 143 mounted to turn on a pivot 144. A segment 145 carried on the end of the arm 142 raises and lowers a rack 146 which rotates a pinion 147 keyed to a shaft 148. Mounted for rotation with the shaft 148 is a gear 149 which meshes with a rack section 150 of the rack bar 134 to advance and retract the same all in a manner described above.

With the description of the various instrumentalities forming the invention completed, their coordinate action may be now summarized. For such analysis, one winding cycle of one unit will be related and it will be assumed that the previous cycle has ended with a wound bobbin in the chuck 12^a and with the chain feed ratchet 90 positioned to take up another tooth.

As the winding operation is completed, the shear cam 141 through its associated elements, advances the rack arm 134 to its forward position and similarly, the centering slide cam 62 retracts the centering slide 13 to release the wound bobbin from the chuck 12^a. This extends the strand 122 from its source to the trough 27 intermediate the fingers 137, 138 and the chuck 12^a. Simultaneously with the withdrawal of the centering slide 13, the toggle 71 is operative to advance and return the plunger 60 in an idle stroke. Next, the rack bar 134 is retracted and the strand is pulled into the clamping and shearing device 121 by the finger 137 where it is sheared and also clamped to position the same across the open mouth of the chuck 12^a. The carrier arm 25 then advances under the action of the barrel

cam 52 to its position illustrated in Fig. 5. This moves the cradle 26 to position an empty bobbin for clamping in the chuck 12^a and the trough 27 into alignment with the conveyer 16 and into operative relation to the plunger 60. The centering slide 13 is then advanced, and at the same time the plunger 60 is driven forward to press the trough 27 together with its wound bobbin to carry the latter onto one of the pins 17 of the conveyer. The forward action of the centering slide forces the running strand together with the empty bobbin into the chuck. To complete the cycle, the plunger 60 is retracted, positioning the roller 41 in alignment with the groove 78 in the bracket 43, whereupon the arm 25 is returned to its initial position. Retraction of the plunger permits the trough 27 to be returned by the spring 79 into a position clear of the chain. Thereupon the ratchet 90, driven by its cam 107, advances another pin on the conveyer into position where it is clamped by the clamping device 91. As the cycle is repeated, a number of bobbins are stored on the conveyer and slowly moved over a long vertical run for removal at the will of an operator.

I claim as my invention:

1. In a bobbin winding machine, a bobbin winding mechanism, an endless conveyer having an elongated vertical run disposed laterally of the winding mechanism, a series of bobbin holders movable with the conveyer, a bobbin transfer mechanism, and means for actuating said conveyer and transfer mechanism in timed relation to each other whereby the transfer mechanism receives wound bobbins from the winding mechanism and delivers the same to the bobbin holders successively.

2. A bobbin winding machine comprising, in combination, an endless conveyer chain, a series of uniformly spaced bobbin holders movable with said chain, a bobbin winding mechanism, and means operative in timed relation to said conveyer adapted to receive wound bobbins from the winding mechanism and to transfer the same to said bobbin holders successively.

3. In a bobbin winding machine having a winding spindle and a wound bobbin storage conveyer providing individual bobbin supports, the combination of a bobbin transfer means comprising a trough for receiving a bobbin dropped from said winding spindle, a carrier for mounting said trough and movable between said spindle and said conveyer to deposit a bobbin on the latter, and means for moving said conveyer in timed relationship with said carrier.

4. A bobbin winding machine comprising, in combination, a winding mechanism including a horizontally disposed winding spindle, an endless chain conveyer disposed at one side of the spindle, a series of bobbin supports movable with the conveyer, means for actuating said conveyer to advance said supports successively into a loading position in spaced parallel relation to the spindle, and means operating in timed relation to the conveyer for receiving wound bobbins from the winding mechanism and transferring the same successively to said supports while in said loading position.

5. In a bobbin winding machine having a winding mechanism with a horizontally disposed winding spindle, a chain having a vertical run at one side of the spindle, a series of bobbin holders movable with said chain, means for advancing the chain to carry said holders successively into a loading position in spaced parallel relation to

the spindle, and a transfer mechanism operating in timed relation to the chain and including a receptacle for receiving a wound bobbin from the winding mechanism, a support for shifting the receptacle into a delivery position with its bobbin in alignment with a bobbin holder in said loading position, and means for shifting the receptacle in a direction axially of such holder to place the bobbin thereon.

6. In a bobbin winding machine, the combination of a winding mechanism having a winding spindle, a wound bobbin storage medium disposed at one side of the winding spindle and having a series of individual supports parallel with the spindle, a receptacle for receiving wound bobbins from the winding mechanism, a support for said receptacle shiftable from a bobbin receiving position laterally to a bobbin discharge position with the wound bobbin aligned with one of said supports, means for advancing the storage medium to present said supports successively to a bobbin loading position, and means for advancing the receptacle to place a bobbin therein onto the support in the loading position.

7. A bobbin winding machine comprising, in combination, a winding mechanism including a spindle, a storage medium for wound bobbins having a series of individual supports shiftable successively into a loading position in predetermined relation to the winding spindle, a carrier for receiving a wound bobbin from the winding mechanism and delivering the same to a support in said loading position, means including a reciprocity actuator for loading the wound bobbin in said carrier onto a support, and means for holding the storage medium against movement during such loading operation.

8. In a bobbin winding machine having a winding spindle and a wound bobbin storage conveyer providing individual bobbin supports, the combination of a bobbin transfer mechanism operable between said winding spindle and said storage conveyer to align wound bobbins with said bobbin supports successively, said transfer means including a movable bobbin holder, and means for moving said bobbin holder axially of the bobbin supports to press wound bobbins thereon.

9. A bobbin winding machine comprising, in combination, a winding mechanism including a horizontally disposed winding spindle, an endless chain conveyer having an elongated run disposed at one side of the spindle, a series of individual bobbin supports movable with the conveyer, means for actuating said conveyer to advance said supports successively into a loading position in spaced parallel relation to the spindle, means operating in timed relation to the conveyer for receiving a wound bobbin from the winding mechanism and transferring the same to said support in said loading position, the last mentioned means including a laterally shiftable member, and a receptacle mounted on said member and shiftable in a direction axially of said support.

10. In a bobbin winding machine having a winding spindle, a wound bobbin storage conveyer, means imparting a step-by-step movement to the conveyer, a doffing mechanism comprising a swinging carrier arm having a trough mounted thereon, and means for moving said carrier arm to shift said trough from a position below and forwardly of said spindle to a position opposite said storage conveyer in timed relationship with the movement of the conveyer.

11. In a bobbin winding machine having a

winding spindle, a doffing mechanism comprising a bobbin receiving receptacle shaped to support a wound bobbin solely by its tip and head ends, and means supporting said receptacle for movement from a receiving position beneath said spindle to a delivery position laterally of the spindle.

12. In a bobbin winding machine having a bobbin winding mechanism with a horizontally disposed winding spindle, a wound bobbin storage medium having a series of individual bobbin supports, means for advancing the storage medium to carry said supports successively into a loading position in spaced relation to the spindle, and a transfer mechanism operating in timed relation to the storage medium and including an elongated trough and a support for said trough shiftable to carry the trough from a bobbin receiving position below the winding spindle into a loading position with the bobbin therein disposed in alignment with one of said supports, said trough being shaped for engagement solely by the tip and head ends only of the wound bobbin, and means for shifting the trough in a direction axially of the bobbin therein to place it upon one of said supports.

13. In a bobbin winding machine having a winding mechanism with a horizontally disposed winding spindle, a storage medium disposed at one side of the spindle and having a series of bobbin holders supported in uniformly spaced relation parallel with the spindle, means for actuating said storage medium to advance said holders successively into a loading position in spaced parallel relation to the spindle, and means operating in timed relation to the storage medium for receiving wound bobbins from the winding mechanism and transferring the same successively to said supports while in said loading position, said transferring means including a trough-like receptacle adapted to support a wound bobbin solely by its tip and head ends, a support upon which said receptacle is mounted for movement in a direction axially of the bobbin, and means for shifting the trough longitudinally to advance the bobbin therein onto a support in the loading position.

14. A bobbin winding machine comprising, in combination, a winding mechanism including a horizontally disposed winding spindle, a wound bobbin storage medium disposed at one side of said spindle and having a series of bobbin holders mounted thereon, means for actuating said storage medium to advance said holders successively into a loading position in spaced parallel relation to the spindle, means for receiving the wound bobbins from the winding mechanism comprising an elongated trough, means for supporting said trough for movement from a position below and forwardly of the winding spindle laterally thereof to deliver a wound bobbin into alignment with a support in said loading position, said trough being closed at its forward end and open at its rear end adjacent the conveyer, and means operating in timed relation to the storage medium for shifting said trough rearwardly relative to its support whereby to position a wound bobbin therein onto the bobbin support then in loading position.

15. In a bobbin winding machine, the combination of a storage medium for wound bobbins having a series of spaced holders thereon, means for actuating the storage medium to advance said holders successively into a loading position, and mechanism operating in timed relation to the

storage medium to deliver wound bobbins to said holders successively while in said loading position, said mechanism comprising a receptacle, a power actuated support for shifting said receptacle transversely from a receiving position to a delivery position aligned with said holder, and a power actuated plunger movable axially of the holder in the loading position, said receptacle having a disengageable connection with said plunger rendered effective as an incident to the lateral shift of the receptacle into said delivery position.

16. In a bobbin winding machine, the combination of a wound bobbin storage medium having a series of spaced parallel bobbin holders, means for advancing said medium to carry said holders successively into a predetermined loading position, a wound bobbin support shiftable transversely of the holders while in said loading position to a delivery position adjacent the storage medium, means for transferring wound bobbins from the support to the bobbin holders while in said loading position including a power actuated member, and means providing a disengagable connection between said receptacle and said member rendered effective in the movement of the receptacle into its delivery position.

17. In a bobbin winding machine, the combination of a wound bobbin storage medium having a series of bobbin supporting elements, means for actuating said storage medium to advance said elements successively into a predetermined loading position, a wound bobbin supporting receptacle, means supporting said receptacle for shifting movement in a direction transversely of the path of movement of the bobbin supporting elements and adapted to present wound bobbins in said receptacle into alinement with a supporting element in said loading position successively, said supporting means including a member having a supporting roller, a trackway engageable by said roller, and an actuating arm pivotally connected to said member.

18. In a bobbin winding machine, the combination of a storage conveyer, a series of spaced bobbin holders movable with the conveyer, means for actuating said conveyer to advance said holders successively into a horizontal loading position, a wound bobbin receptacle, means supporting said receptacle for movement transversely of the conveyer to a delivery position opposite the holders while in said loading position, said supporting means including a guideway disposed transversely of the conveyer at one side thereof, and a member movable along said guideway and carrying said receptacle.

19. In a bobbin winding machine, the combination of a storage medium comprising a series of spaced bobbin holders, means for actuating said medium to advance said holders successively into a horizontal loading position, a wound bobbin receptacle, means supporting said receptacle for movement to a delivery position opposite the holders while in said loading position, said supporting means including a track disposed transversely of the conveyer at one side thereof, a member guided by said track and carrying said receptacle, a power actuated device movable to shift the receptacle in a direction axially of the holders while in their loading position, and means operative as an incident to the movement of said trough into its delivery position to establish a driving connection between said device and said receptacle.

20. A bobbin winding machine comprising, in

combination, a bobbin winding mechanism including a spindle having a bobbin gripping chuck and a tail center releasably holding a bobbin being wound, a storage medium for wound bobbins comprising a series of bobbin holders, means for actuating said storage medium to present said bobbin holders successively to a predetermined loading position, means for delivering wound bobbins to said bobbin holders as they are successively presented to said loading position including a device operable in a direction axially of the holders while in said loading position, and power actuated means for shifting said tail center and said device in timed relation to each other.

21. A bobbin winding machine comprising, in combination, a bobbin winding mechanism including a spindle having a bobbin gripping chuck and a tail center releasably holding a bobbin being wound, a storage medium for wound bobbins comprising a series of bobbin holders, means for actuating said storage medium to present said bobbin holders successively to a predetermined loading position, means for delivering wound bobbins to said bobbin holders as they are successively presented to said loading position including a device operable in a direction axially of the holders while in said loading position, and power actuated means including a cam for operating the device.

30 22. In a bobbin winding machine, a wound
bobbin storage conveyer chain having a series of
individual bobbin receiving pins, means for ac-
tuating said conveyer to present said pins suc-
35 cessively into a predetermined loading position, and
means yieldably engaging opposite sides of the
pins for holding said pins in such loading posi-
tion.

23. A bobbin winding machine comprising, in combination, a winding mechanism including a spindle, a wound bobbin storage conveyer having a series of individual bobbin holders, means for actuating said conveyer to advance said holders successively into a predetermined loading position in parallel relation to the spindle, means for delivering wound bobbins from the winding mechanism to successively presented holders, and yieldable means acting on said conveyer to maintain said holders in loading position during the transfer of the wound bobbins thereto.

24. In a bobbin winding machine, a wound bobbin storage conveyer having a series of individual bobbin receiving pins, means for actuating said conveyer to present said pins successively into a predetermined loading position, and means yieldably holding said pins in loading position including a pair of spring pressed dogs engaging successive pins in their advance toward said loading position.

60 25. In a bobbin winding machine, a wound bobbin storage chain having a series of individual bobbin supporting elements, means for actuating said chain to advance said elements into a pre-determined loading position, means for delivering wound bobbins to said elements while in said loading position, said chain having an elongated upright run into which said elements are advanced when loaded, and guide means coacting with the 65 70 chain to hold said elements in spaced parallel relation including guide members rigid with the respective elements and a guideway for receiving said members.

26. A bobbin winding machine having, in combination, a winding mechanism including a spin-

die, a wound bobbin receptacle disposed forwardly of the spindle below the axis thereof, a stationary shear and clamp device disposed rearwardly of and somewhat above said receptacle and including a movable shearing and clamping member, a power actuated plunger reciprocable parallel with said receptacle, means operative upon the release of a bobbin into the receptacle to draw the running strand rearwardly into said shearing and clamping device, said means including a member on the forward end of said plunger for engaging the running strand, and means also carried on said plunger and operative to engage said shearing and clamping member to actuate it.

27. In a bobbin winding machine, means for winding a bobbin, means for storing empty bobbins, a traveling storage medium for wound bobbins, and means for simultaneously transferring an empty bobbin from said storing means to said winding means and a wound bobbin from the latter to said storage medium.

28. In a bobbin winding machine, a winding spindle, an empty bobbin magazine, a wound bobbin storage conveyer, and a bobbin transfer mechanism operatively associated with said magazine, spindle, and conveyer for simultaneously transporting an empty bobbin from said magazine to said spindle, and a wound bobbin from the spindle to the conveyer.

29. In a bobbin winding machine having an empty bobbin magazine, a winding spindle, a donning and doffing mechanism comprising a movable support, a plurality of bobbin receiving receptacles mounted on said support, and means for displacing said support from a first position to a second position to thereby position said receptacles to place an empty bobbin in said spindle and to move a wound bobbin from said spindle to a point of removal simultaneously.

30. In a bobbin winding machine, a winding mechanism having a spindle, an empty bobbin magazine and a storage conveyer disposed laterally on opposite sides of said spindle, and a bobbin transfer mechanism comprising a movable carrier arm supporting two bobbins in spaced relation with each other, said arm being movable to a first position for receiving an empty bobbin from the magazine and a wound bobbin from the spindle and to a second position to place said empty bobbin for clamping in said spindle and said wound bobbin for displacement onto said conveyer.

31. In a bobbin winding machine having an empty bobbin magazine and a winding spindle arranged in spaced relation, a donning and doffing mechanism comprising a movable support, a plurality of bobbin receiving receptacles mounted upon said support and including an empty bobbin receptacle and a filled bobbin receptacle respectively disposed beneath said magazine and said winding spindle, and means for actuating said support to carry said empty bobbin receptacle into operative association with the spindle and said filled bobbin receptacle to a point of removal of the bobbin at one side of the spindle.

32. In a bobbin winding machine, the combination of a winding spindle, an empty bobbin magazine disposed at one side of the spindle, a wound bobbin storage means at the other side of the spindle, a donning and doffing mechanism comprising an empty bobbin receptacle positioned beneath said magazine and a filled bobbin receptacle positioned beneath said spindle, and

means operative simultaneously to shift said receptacles to transfer an empty bobbin into operative association with the spindle and a filled bobbin into operative association with said storage means.

33. A bobbin winding machine having, in combination, a winding spindle including means for gripping a bobbin to be wound, an empty bobbin magazine disposed at one side of the spindle, a storage medium for filled bobbins disposed at the other side of the spindle and having a series of bobbin holders for receiving wound bobbins, a donning and doffing mechanism comprising an empty bobbin receptacle positioned in operative association with the magazine and a filled bobbin receptacle positioned in operative association with the spindle, means operative to shift said two receptacles simultaneously to carry an empty bobbin into operative association with the spindle and a filled bobbin into operative association with said storage means, means for transferring the filled bobbin onto one of said holders, and means acting concurrently to actuate said bobbin gripping means and said transferring means whereby to clamp the empty bobbin in winding position and to shift the wound bobbin onto a bobbin holder of the storage means.

34. In a bobbin winding machine, bobbin winding means including a spindle having bobbin holding means, a storage medium spaced from said spindle and having a series of bobbin holding devices, a receptacle supported for movement from a position beneath the spindle to a position in operative association with the storage medium, means for transferring a wound bobbin in said receptacle onto a bobbin holder on the storage medium, and means for actuating said receptacle, said storage medium and said transfer means in timed relation to each other.

35. A bobbin winding machine comprising, in combination, a bobbin winding mechanism having a spindle with means for releasably holding bobbins being wound, storage means for the wound bobbins including a series of bobbin holders, conveyer means for advancing the holders successively into a predetermined loading position, means for transferring wound bobbins upon release by said holding means of the winding mechanism from a position underlying the spindle into said loading position, said transferring means including a support mounted for movement in a direction transversely of the axis of the bobbin, and a receptacle movable axially on said support, and means for shifting said receptacle axially to carry the bobbins onto the holders while in said loading position.

36. A bobbin winding machine comprising, in combination, a bobbin winding mechanism including a horizontally disposed spindle and means releasably holding the bobbin thereon, storage means for receiving wound bobbins including a series of bobbin holders, a conveyer means for advancing the holders successively into a predetermined loading position with the holders disposed on axes disposed parallel with the winding spindle, means for receiving wound bobbins released by said holding means of the winding mechanism and operative to carry them into said loading position successively including a trough-like receptacle for supporting the top and head ends only of the wound bobbins, a movable support for carrying said receptacle into said loading position, and means acting upon said receptacle in said loading position operative to shift the bobbins therein onto awaiting bobbin holders.

37. In a bobbin winding machine, a storage means comprising a series of bobbin holders, means for advancing said bobbin holders with a step-by-step motion into a predetermined loading position successively, an actuator reciprocable toward and from the bobbin holders in said loading position, means for conveying wound bobbins into said loading position including a receptacle and a member connected thereto and movable into and out of driving relation to said actuator.
